UNITED STATES PATENT OFFICE

WILLIAM WALLACE KILGORE, OF ATLANTA, GEORGIA, ASSIGNOR TO ALL METAL BOTTLE COOLER CORPORATION, OF ATLANTA, GEORGIA, A CORPORATION OF GEORGIA

DESIGN FOR A COMBINATION BOTTLE COOLER AND STAND

Application filed June 27, 1931. Serial No. 40,348. Term of patent 14 years.

To all whom it may concern:

Be it known that I, WILLIAM W. KILGORE, citizen of the United States, residing at Atlanta, in the county of Fulton and State of Georgia, have invented a new, original, and ornamental Design for a Combination Bottle Cooler and Stand, as shown in the accompanying drawings and described in the following specification.

Figure 1 is a perspective of the combination bottle cooler and stand; and

Figure 2 is a detail in perspective of the leg.

I claim:

The ornamental design for a combination bottle cooler and stand as shown.

WILLIAM WALLACE KILGORE.
